UNITED STATES PATENT OFFICE.

CHARLES B. CLARK, OF DETROIT, MICHIGAN.

LOCK-HINGE.

SPECIFICATION forming part of Letters Patent No. 249,304, dated November 8, 1881.

Application filed August 17, 1881. (Model.)

To all whom it may concern:

Be it known that I, CHARLES B. CLARK, a citizen of the United States, residing at Detroit, in the county of Wayne and State of Michigan, have invented new and useful Improvements in Hinges for Window-Blinds, of which the following is a specification.

My invention relates to that general class of hinges which, when the blind is thrown open, lock it in that position, the blind being closed by forcibly causing it to rise on the pintle of the hinges and swing past the locking shoulders or inclines.

The object of my invention is to improve the construction and operation of hinges of this general character.

The construction of the hinge will be fully hereinafter described in detail, and the improvements specifically pointed out in the claim.

In the accompanying drawings, illustrating my invention, Figure 1 is a front view of the improved blind-hinges, shown as being connected with the stile of a shutter and jamb of a window, the shutter being closed. Fig. 2 is a perspective view of the leaf carrying the female portion of the hinge. Fig. 3 is a perspective of the leaf which carries the pintle or male portion of the hinge. Fig. 4 is a rear view of the hinge applied as in Fig. 1, showing the shutter open and hinge locked.

The letter A indicates the male portion of the hinge which is to be secured to the jamb or side of the window. The upper end, b, of the pintle B is cylindrical and the remainder is rectangular in cross-section, the portion marked b' being conical. That portion c of the knuckle or bracket C between the pintle and the leaf D is elevated or formed higher than the remaining part, c', and there is an incline, d, leading from the lower part, c', to the higher part, c. The eye E of the female part F is of a conical shape corresponding to the conical part of the pintle, and the knuckle or bracket G has a flange, g, the end g' of which is inclined. The bracket C is notched at h, to permit the lug i on the other portion of the hinge

to pass in putting the hinge together, as is usual.

When the blind is thrown back, as shown in Fig. 4, the eye fits down over the conical part of the pintle, the square faces of the eye and pintle being in contact. This locks the blind, and it can only be moved by forcibly pulling it, when, the faces in the eye being thrown against the angles or corners of the conical part of the pintle, the blind will rise until the eye reaches a point on the pintle of a sufficiently small diameter to allow it to move past the angular corners, when it will again sink onto the pintle and lock the blind in the half-closed position shown in Fig. 2. When the blind is drawn from this position to close it the eye will again rise, as just described, until the flange g rides upon the raised portion c of the bracket C, after which the movement of the blind will be perfectly horizontal, the flange g and elevation c giving it a perfectly level support. This last movement of the hinge is facilitated by the inclines c' and g', which aid in raising the flange onto the higher part, c, of the bracket C.

It will be observed that the only motions that the eye has on the pintle are rotary and vertical, and that there is no lateral movement of any of the parts.

I do not broadly claim a blind-hinge constructed with an angular base to its pin or axis, and with an angular socket part way through its sleeve, adapted to fit down over the angular base of the pin or axis, as such is not new with me; but

What I claim is—

In a blind-hinge, the combination of the male portion of a hinge, having the raised part c and a conical polygonal pintle, with the female portion having a conical polygonal eye and flange g.

In testimony whereof I have hereunto set my hand in the presence of two subscribing witnesses.

CHARLES B. CLARK.
